UNITED STATES PATENT OFFICE.

WILLIAM J. KEELEY, OF NEW YORK, N. Y.

ACCENTING ATTACHMENT FOR MUSIC-PLAYING DEVICES.

1,107,801.

Specification of Letters Patent. Patented Aug. 18, 1914.

Application filed March 30, 1910. Serial No. 552,407.

To all whom it may concern:

Be it known that I, WILLIAM J. KEELEY, a citizen of the United States, residing at New York, in the county of New York and 5 State of New York, have invented a new and useful Accenting Attachment for Music-Playing Devices, of which the following is a specification.

This invention relates to a music playing 10 device, and the principal object thereof is to provide means whereby the operator may accent or bring out any melody note or series of notes in a musical composition while the accompanying and foundation tones are subdued.

The invention may be applied to all kinds 15 of automatic music playing instruments, including the so-called cabinet piano players of various makes and constructions.

20 In accomplishing the object of the invention the perforated music-sheets are provided with marks to designate the melody notes, or to indicate when the accenting device is to be operated.

25 The means which I have provided for accomplishing the desired result in connection with the marked music-sheets consists of an adjustable bar adapted to subdue the accompanying and foundation tones, and having 30 means for permitting the melody notes to be sounded with full power.

Reference is to be had to the accompanying drawings which illustrate certain embodiments of the invention as applied to two 35 different kinds of musical instruments.

Figure 1 is a vertical sectional view of a part of one form of an automatic piano with my invention applied thereto. Fig. 2 is a similar sectional view of a piano player also 40 provided with my invention, and Fig. 3 is a perspective view of the mechanism employed in Fig. 1, the ordinary parts of the piano being removed to show the interior construction, and also illustrating a form of 45 music sheet which can be employed.

Referring first to Fig. 1, it will be seen that located adjacent to the hammers *a* in such position as to be engaged by the shanks *a'* is a bar *b*. This bar is preferably covered 50 with a layer of felt *b'* or similar soft material on the face against which the shanks of the hammers strike. This prevents the

hammers from clicking or making a noise when they engage the bar *b*. This bar is shown in Fig. 3 as mounted in guides *c* so 55 as to slide longitudinally into proper position to be engaged by the desired shanks *a'*. It is also provided with one or more slots *b*². When applied to a piano such as shown in Fig. 1, these slots will be vertically arranged 60 in the front face of the bar, and are designed to permit any hammer shank which may be selected to deliver its blow with full force without engaging the felt, the others of that octave striking the soft surface to produce 65 subdued tones.

In order that the bar may be adjusted it is shown as provided with a rod *d* connected with an arm *e* mounted on an oscillating shaft *f*. Another arm *g* on this shaft serves 70 to turn it and this arm is connected by a link *h* with an operating lever *k*. This operating lever has a handle *k'*, and is connected with a pointer *m* which is adapted to move over a portion of the music sheet *o*. 75

When so constructed that the bar *b* has only one slot *b*², in order that the device may have full range, it will be necessary to make it as short as possible and move it nearly the full length of the instrument so 80 that the slot may be adjusted in such position as to receive any one of the hammer shanks *a'*. In this case the pointer *m* is also designed to move the whole length of the music-sheet, so that it may be brought 85 to any desired note. This is done if the notes are marked individually by asterisks, stars, or the like, which is one way in which the invention may be carried out. However, if desired, the notes on the music sheet may 90 be indicated at one side thereof by a line, a series of dots, or other marks, and in that case the pointer *m* will move only far enough to cover the marks indicating all the notes.

In the form which I have illustrated, I 95 have shown the bar as provided with a plurality of slots *b*² each one corresponding to an octave, a fifth or a third; in the present instance, to an octave. In this case it is necessary to move the bar only the space occupied by an octave, and the pointer *m* moves a corresponding distance on the music sheets or across the indications at the edge thereof. In the use of the device, (the

music sheet being marked to indicate the accented melody notes in either one of the ways indicated above), the pointer is operated by hand through the handle *h'* to bring it successively to the marked positions. This moves the bar *d* through the instrumentality of the links and arms described, or in any other desired way, so that for each octave, the slot *b*² is in position to receive the hammer-shank corresponding to the note indicated by the pointer *m*. It will be understood, of course, that this bar should be operated longitudinally only when the hammers are all back in their normal positions, because if any one of them is forward in one of the slots *b*² it would prevent operation of the bar.

Of course the pointer *m* may move across the music-sheet at any point thereof, but it may conveniently do so as the sheet travels over the tracker board.

When the bar *b* is not in use, it can be disposed of in any desired way in accordance with the construction of the instrument on which it is placed. A most convenient way for most instruments is to allow it to drop down to clear the hammer-shanks of the piano action. If desired, when the device is constructed with a plurality of slots *b*², as shown, there can be a plurality of pointers so distanced as to indicate octaves.

In Fig. 2 I have shown how the device may be applied to so-called cabinet piano players by placing it under the fingers *p* which strike the keys of the piano. This construction comes within the scope of my invention.

While I have illustrated and described two particular applications of my invention, and one form in which I at present prefer to embody it, I am aware that many modifications may be made therein, and that when applied to different makes of musical instruments, certain modifications will be necessary, all of which come within the scope of the skill of any person skilled in this art, and also within the scope of my invention as expressed in the claims.

Having thus fully described my invention, what I claim is:

1. A music playing device having a movable bar provided with means for receiving the blows from the hammer shanks as they move toward the strings to lessen the power of the blows imparted to the strings, the bar being provided with a slot for receiving a hammer shank, whereby one of the strings may be struck with full force.

2. A music playing device having a movable bar provided with means to lessen the power of the blows imparted to the strings representing an octave, the bar being provided with a slot for receiving a hammer shank for sounding the melody note, whereby the melody note of that octave may be

sounded with full force while the accompanying and foundation tones are subdued by said bar.

3. A music playing device having hammers, and adjusting means for engaging a plurality of hammer-shanks as they move toward the strings and subduing the accompanying and foundation tones, and having means fixed relatively to said adjusting means for preventing a melody note from being subdued.

4. In a music playing device, the combination with hammers and strings, of a bar having a soft surface in position to be engaged by the hammers as they approach the strings for subduing certain tones of a section, the hammer engaging surface of said bar extending throughout the length occupied by all the hammers but one of a section, whereby one hammer can strike with full force the string for producing the melody note.

5. In a music playing device, the combination of the hammers, a sliding bar movable between the hammers and strings in position to engage the shanks of the hammers and lessen the blows delivered by them, said bar having slots to permit certain of the hammer shanks to deliver a blow of full force.

6. In a music playing device, the combination with the hammers and strings, of a sliding bar movable between the hammers and strings in position to engage the shanks of the hammers and lessen the blows delivered by them, and having slots arranged at regular distances apart so as to register with corresponding hammers of each section.

7. In a music playing device, the combination with the hammers and strings, of a sliding bar in position to engage the shanks of the hammers and lessen the blows delivered by them, said bar having a plurality of slots arranged at regular distances apart so as to register with corresponding hammers of each section, guides for said bar, a pointer movable over the music-sheet, and means for simultaneously moving the pointer and bar.

8. In a music playing device, the combination of the hammers, a sliding bar movable between the hammers and strings in position to engage the shanks of the hammers and lessen the blows delivered by them, said bar having slots to permit certain of the hammer shanks to deliver a blow of full force, a pointer movable over the music sheet, and means for simultaneously moving the bar and pointer equivalent distances.

9. In a music playing device, the combination of a sliding bar having a series of slots, a pointer adapted to move over a music sheet, means for simultaneously moving the bar and pointer, and a music sheet having marks representing melody notes located in the path of said pointer.

10. In a music playing device, the combi-

nation of the hammers, movable means for
engaging the shanks of the hammers to
lessen the blows delivered by them, said
means having slots to permit certain of the
5 hammer shanks to deliver a blow of full
force, a pointer movable over the music
sheet, and means for simultaneously moving
said means and pointer equivalent distances.

In testimony whereof I have hereunto set
my hand, in the presence of two subscribing 10
witnesses.

WM. J. KEELEY.
